VALANCE, CURTAIN AND DRAPERY
FIXTURE, AND ACCESSORY

Mary Nealis, Detroit, Mich.

Application November 12, 1947, Serial No. 785,459

6 Claims. (Cl. 160—21)

1

This invention relates to improvements in window ornamentation of the type including a valance, curtains and draperies and more particularly relates to an improved valance supporting structure which enables the use of a simple tubular sleeve of fabric detachably mounted on the valance support. This invention further concerns the combination of such a valance with a drapery and curtain fixture attached to the bracket forming the support for the valance, the drapery fixture conforming in shape to the external shape of the valance to provide a pleasing decorative appearance.

Heretofore valance constructions have commonly consisted of a solid backing material to which the desired decorating fabric could be attached by standard and well known upholstering techniques. Such constructions are subject to many disadvantages, one of the more important of which is that the installation requires the skilled labor of carpenters, upholsterers, etc., making the installation relatively expensive. A second disadvantage of valances of this type lies in the inability of the housekeeper to remove the decorating fabric from the valance structure for purposes of cleaning, replacing, etc., without seriously damaging the fabric.

It is therefore one of the objects of this invention to provide a valance bracket structure adapted to detachably receive a prefabricated simple tubular sleeve of decorating fabric and capable of being demountably secured to a window-type opening.

Another object of this invention is to provide a valance bracket structure which is provided with means for demountably securing the same to a window-type opening which readily allows the housewife to handle the assembly as a unit and to envelop the decorating fabric on the assembly at floor height and thereafter place the entire unit in position.

A further object of this invention is to provide a window ornamentation having in combination a valance bracket structure adapted to be slidably enveloped by a simple tubular decorative fabric, and a drapery and curtain fixture detachably mounted on a single supporting means, the drapery and curtain fixture having an external shape conforming to that of the valance structure.

A still further object of the invention is to provide a simple and inexpensive hanger bracket for securing a valance bracket structure and a drapery and curtain fixture in vertically spaced relationship.

2

Other objects and advantageous features of the invention will become apparent or will be specifically pointed out in the specification when taken in conjunction with the accompanying drawing 5 wherein:

Figure 1 is a perspective view of the assembled valance bracket structure and drapery and curtain fixture mounted in position;

Figure 2 is a perspective view showing the 10 valance bracket structure of Figure 1 with the decorating fabric, draperies and curtains removed therefrom;

Figure 3 is a perspective view showing the 15 drapery and curtain fixture in attachment with the combination hanger bracket; and

Figure 4 is a perspective view showing further 20 details of the hanger bracket.

Referring more particularly to the drawing, there is shown in Figure 1 a box shape valance 20 having an elongated rectangular shaped front panel 1 and generally rectangular end panels 2 and 3 which valance is adapted for mounting in front of a window-like aperture. Panels 1, 2 and 3 are formed of a stretched decorative fabric 15 and the valance is supported by arms 19 and 28 which are attached to hanger brackets 20 and 29 respectively. Draperies 4 and 5 extend vertically downwardly from panel 1 and traverse the aperture approximately parallel to panel 1. The draperies 4 and 5 conform in general to the shape 30 of the valance as may be seen by the drapery portion 6 extending rearwardly toward the wall in parallelism with panel 3. Positioned somewhat rearwardly of draperies 4 and 5 is curtain 35 7 which forms the central portion of the aperture ornamentation.

As may be seen in Figure 2, the valance skeleton is shown consisting of a valance bracket structure, generally designated 10, which comprises a 40 pair of bracket members 11 and 12 having arms 13, 14, 15 and 16 connected by telescoping rod or tube members 17 and 18. Bracket member 11 is provided with an upper U-shaped member having a rod supporting arm 13, an attachment arm 19 and a supporting portion 11a which is the bight portion of the U-shaped member. An L-shaped member having a rod-supporting arm 14 and a supporting portion 21 is positioned directly beneath the upper U-shaped member and vertically spaced therefrom by rigid end plate 22. End plate 22 has a generally rectangular shape and is preferably fabricated from thin sheet metal inasmuch as its primary purpose is to strengthen and reinforce supporting portions 11 and 21. A 45 second purpose served by said plate 22 is to pro-

vide a closed end structure which is pleasant in appearance in the absence of the decorative covering fabric. Materials which are much weaker in tension and shear may also be satisfactorily utilized, for example, cardboard which has been reinforced at its rearward edge 23 and forward edge 23a. Bracket 12 is similar in construction to that of bracket 11 and it may be clearly seen that end surface member 24 overlaps and extends around the corners formed by the intersections of arm 15 and supporting portion 12a, arm 16 and supporting portion 25 thereby forming end facings 26 and 27. It will be apparent that end facings 23, 23a, 26 and 27 contribute to the provision of relatively smooth extensions of the supporting portions of brackets 11 and 12. The rounded corners thus formed enable a simple tubular valance of decorating fabric to be slid over the arm 19 across end surface 22, continuously across tubular members 17 and 18, around bracket 12 and ending at end surface 26. A tubular valance formed of limp decorating material may alternatively be first slid over tubes 17 and 18 in gathered form, after which brackets 11 and 12 may be telescopically attached thereto and the gathered decorating fabric easily slid over each of the brackets 11 and 12 to form a continuous valance covering.

An un wrinkled and solid-appearing covering for the valance structure is produced by longitudinally separating brackets 11 and 12 and positioning their supporting arms 19 and 28 in hanger brackets 20 and 29 respectively. Brackets 11 and 12 maintain the new positions continuously stretching the fabric due to the friction between arms 19 and 28 and the hanger brackets 20 and 29. Two way stretching of the limp valance material is secured by fabricating the strengthening members 22 and 24 of such vertical dimensions that the valance material forms a relatively tight-fit therewith when slid into position. For extremely wide window apertures which require elongated telescopic members 17 and 18, it is desirable to reinforce them to prevent sagging and to maintain equal vertical spacing and this may be accomplished by positioning a spacer 30 between members 17 and 18 at approximately the median point of the span.

As may be seen in Figures 1 and 4, valance structure 10 may be demountably attached to a supporting means in the form of a hanger bracket such as 20 and 29. Bracket 29 is provided with an upper attachment portion 31 and a lower attachment portion 32 connected by an outwardly projecting generally channel shaped portion 33. Projecting portion 33 is adapted to receive supporting arm 28 which may be positioned therein either by sliding the supporting arm into the rectangular aperture defined by the outwardly projecting portion 33 and the wall surface or by inserting the supporting arm 28 by sliding the same along the wall, deflecting upper portion 31 and snapping the arm into the aperture 34. Obviously, in attaching valance structure 10 to the hangers 20 and 29 only one arm 19 or 28 may be threaded into the aperture and the other arm must be snapped in from the top. The hanger bracket 29 may be suitably attached by means of screw positioned in apertures 35 and may, if necessary, have its upper portion 31 secured by a screw in aperture 36. Integrally connected to lower portion 32 is downwardly depending drapery fixture securing portion 37 which has the form of a tightly-bent perpendicularly disposed U-shaped member having outer return bent por-

tion 38. Portion 37 may be and preferably is positioned slightly outwardly from the plane of the wall, a distance such as that equal to the width of interconnecting generally horizontal portion 39.

5 Drapery and curtain supporting fixture 40 is comprised of a pair of similar brackets 41 and 42 having the general box shape of valance structure 10. Brackets 41 and 42 are comprised of 10 corresponding parts bearing correspondingly primed numbers. Bracket 41 is comprised of horizontal supporting arm 43, outwardly projecting supporting portions 44 and 45 and rod-supporting arms 46 and 47 perpendicular to supporting arms 15 44 and 45 respectively. Supporting arm 44 has a length less than that of arm 45 such that rod-supporting arm 46 is positioned behind and spaced from rod-supporting arm 47. Brackets 41 and 42 are united into one unitary structure by means 20 of the tube members 48 and 49. It is apparent that draperies having the common type hem may be easily slid over each of brackets 41 and 42 and the tube members 48 and 49 thereafter inserted to form the drapery and curtain fixture 25 40. Drapery fixture 40 is adapted to be attached to the U-shaped vertical extension of the hanger bracket defined by portions 31 and 38 by inserting member 43 therein and thereafter lowering clip 50 therearound to provide a tight fit 30 and insure against undesired disassembly. Clip 50 is comprised of an annular portion 51 adapted to surround members 31 and 38 and a vertically depending nib portion 52 adapted to enable the ready manipulation of the clip.

35 The two position construction of the hanger bracket 29 enables the positioning either of the drapery fixture 40 in the U shaped retaining portion or in the upper retaining aperture 34 in periods during which the valance structure has 40 been removed. It will be appreciated that the general box shape valance structure 10 and the corresponding box shaped drapery fixture 40 when assembled on the single supporting means 29 or 20 mutually contribute to produce a unitary 45 aperture ornamentation which has a uniformity of appearance that is striking and pleasing to the eye.

Hanger bracket 29 or 20 is a unitary securing means which positions the top level of the drapery and curtain materials closely adjacent to the lower surface of the valance structure thereby requiring the smallest possible length of drapery and curtain materials and yet the bracket fixture is completely hidden by the valance. The 55 two position hanger enables the removal of the valance without disturbing the draperies and curtains and presents a pleasing appearance even in the absence of the valance especially when the drapery fixture is positioned in the upper aperture 34.

60 I claim:

1. A valance supporting structure comprising a pair of brackets each including at least two rod-supporting arms of cantilever construction, extension rods attached to said arms, means incorporated in each bracket for supporting such arms in vertically spaced substantially horizontal positions in the same vertical plane and parallel to one another, and also parallel to a window opening, including supporting portions extending perpendicularly to such arms, such supporting portions being vertically spaced and positioned conformably to the spacing of such arms and constituting relatively smooth extensions of such 75 arms, whereby a tubular valance formed of limp

material may be slid over the arms and may extend continuously over such supporting portions and over said extension rods attached to such arms.

2. A bracket structure as defined in claim 1 including a hanger bracket to which the said valance supporting structure may be separably attached and a generally rectangular plate connecting said supporting portions, at least one of said supporting portions constituting the bight section of a U-shaped sheet metal member, one arm of said member defining one of said previously mentioned supporting arms and the other arm of said member being engageable with said hanger bracket.

3. A valance supporting structure consisting of a pair of brackets each including at least two rod-supporting arms of cantilever construction, means incorporated in each bracket for supporting such arms in vertically spaced substantially horizontal positions in the same vertical plane and parallel to one another, including supporting portions extending transversely to such arms, such supporting portions being vertically spaced and positioned conformably to the spacing of such arms and constituting relatively smooth extensions of such arms, the upper of said supporting portions being rigidly attached to a transversely extending supporting arm, said rod-supporting arms being connected by extension rods whereby a unitary double U-shaped structure is formed over which a tubular valance may be slid, whereby such a valance may extend continuously over such supporting portions and said extension rods.

4. A window-type aperture ornamentation structure comprising in combination a valance supporting structure having a generally box shape, a drapery and curtain fixture having a

reduced size and a shape corresponding to said valance and a hanger bracket demountably receiving and supporting said valance structure and said fixture, said bracket separating said valance structure and said fixture, and rigidly engaging the same whereby the said valance and fixture are prevented from disengagement and the said fixture is prevented from rotation.

5. An ornamentation structure as defined in claim 4 wherein the said bracket is provided with channel means for receiving said valance structure, said means being accessible from above, and U-shaped means for receiving said fixture, said latter means having releasable securing means for rigidly locating said fixture therein.

6. An ornamentation structure as defined in claim 4 wherein the said bracket is provided with channel means for receiving said valance structure from above, and means for receiving said fixture, said means consisting of a tightly bent vertically disposed U-shaped member the inner wall portions of which define an aperture which is intimately filled by said fixture, and a clip surrounding said U-shaped member locking said fixture in said aperture.
